[57] CLAIM

The ornamental design for an airplane wheel accelerator attachment, as shown and described.

DESCRIPTION

FIG. 1 is a front, top and side perspective view of the airplane wheel accelerator attachment embodying the design of the present invention;

FIG. 2 is a side elevational view thereof, the side opposite being a mirror image of the side shown in FIG. 2;

FIG. 3 is a front elevational view thereof; and,

FIG. 4 is a rear elevational view thereof.
